UNITED STATES PATENT OFFICE.

JAMES M. McCLELLON, OF EVERETT, MASSACHUSETTS.

BOILER.

SPECIFICATION forming part of Letters Patent No. 699,338, dated May 6, 1902.

Application filed July 8, 1901. Serial No. 67,451. (No model.)

To all whom it may concern:

Be it known that I, JAMES M. McCLELLON, a citizen of the United States, residing at Everett, in the county of Middlesex and State of Massachusetts, have invented an Improvement in Boilers, of which the following description, in connection with the accompanying drawings, is a specification, like numerals on the drawings representing like parts.

10 In the ordinary type of tubular boiler, wherein the products of combustion pass through tubes or flues which extend through the body of water in the boiler, the heating of the water in the boiler is accomplished by those gases which in their passage through the flue contact with the sides of the flue, and therefore the central portion of the column of heated gases passes through the flue without yielding up any of its heat to the water. In comparatively small boilers—such as are used in automobiles, steam-launches, and fire-engines—it not infrequently happens that the temperature of the gases escaping through the top of the flues is from 700° to 900° Fahrenheit, thus showing that only a small portion of the heat generated has been absorbed by the water in the boiler.

15 It is the object of my invention to improve this class of boilers by providing means whereby the temperature of the escaping gases may be reduced to practically that of the steam in the boiler, the result being that practically all the heat in the products of combustion above that of the steam is utilized in making steam, and this I accomplish by enclosing in each flue one or more water-tubes which have communication at their ends with the interior of the boiler-shell. Preferably the water-tubes will be arranged in contact 20 with each other and will have a spiral arrangement in the flue, the outer tubes contacting with the interior of the flue, whereby the flue is divided into a plurality of spiral compartments. The products of combustion 25 in passing up the flue are compelled to take the spiral or sinuous course and are therefore not only retained a longer time in the flue, but in their passage through the flue are either contacting with the walls of the flue or 30 with the water-tubes inclosed therein. The result is that the heating-surface is materially

increased, and a much greater economy is obtained.

In the drawings, Figure 1 illustrates a vertical sectional view of a boiler, one of the flues of the boiler being shown in section. Fig. 2 is a section on the line 2 2, Fig. 1. Fig. 3 is a section of the header.

The boiler-shell, which may be of any suitable construction, is designated by 3, it being shown as having secured to the lower portion thereof the apron 4, forming the usual chamber in which the burner or other heating medium is inclosed. Extending through the boiler are the usual flues, (designated generally by 5) these flues being expanded at their ends into the ends of the boiler, as usual, and there being as many such flues as is desired. For the sake of clearness of illustration only three of such flues have been illustrated in Fig. 1. Each flue incloses one or more water-tubes, which extend lengthwise of the flue and have communication at their ends with the exterior of the flue, and my preferred way of arranging these interior water-tubes is illustrated in Figs. 1 and 2. Preferably the ends of the water-tubes are connected to suitable headers, which extend across and are secured to the interior of the flues near their ends. The headers are designated generally by 6, and they are made of any suitable material and have their ends curved, as at 7, to fit the interior of the flues. Each header is provided with a series of sockets of a size to receive the ends of the water-tubes, there being as many such sockets as there are tubes inclosed in the flue. In this embodiment of my invention I employ three such water-tubes, and each header, therefore, has three sockets 8, into which the ends of the water-tubes are secured in any suitable way.

Extending longitudinally through the header and transversely through the flue is an opening 9, which passes through the ends of each of the water-tubes, whereby each of said tubes has a free communication at its ends with the interior of the boiler-shell.

Preferably the central water-tube 10 will be straight, as seen in Fig. 1, and will extend centrally of the flue 5. The outside tubes 11 are preferably spirally arranged and are of such a size that they are in contact with the

central tube 10 and with the inner wall of the flue 5, thus dividing the interior of each flue into two sinuous compartments. In this construction it will be seen that as the heated 5 gases pass up through the flues they are divided into two currents, which are compelled to take the sinuous course, and the heated gases not only contact with the inner wall of the flue 5, and thus heat the water in the 10 boiler, but they also operate to heat the water in the water-tubes 10 and 11, and as these water-tubes have free communication with the interior of the boiler at both their ends the steam generated in said tubes will escape 15 at the upper end thereof in the boiler-shell. Furthermore, because of the sinuous course which the heated gases are compelled to take they are retained longer in the flues and yield up a greater portion of their heat than if they 20 passed straight from the tube. I have found by experiment that the gases issuing from the top of the flues have a temperature of only about 300° Fahrenheit instead of 700° or 800°, as is the case when they pass directly 25 through the flue.

To insure dry steam, I deem it advisable to place my upper header 6 some distance below the top of the boiler, as seen in Fig. 1.

In the construction of my boiler the water- 30 tubes will be brazed or otherwise secured to the headers, and the headers and water-tubes will then be slipped into the flues and the headers secured thereto. When thus constructed, the flues may be expanded in the 35 boiler, as usual.

While I have illustrated herein one particular arrangement for the water-tubes, yet I do not wish to be confined thereto, for, believing that I am the first to employ a water- 40 tube in the interior of the flue of a tubular boiler, I desire to claim the same broadly.

Having described my invention, what I claim, and desire to secure by Letters Patent, is—

45 1. A flue for a boiler, having inclosed therein and extending longitudinally thereof a plurality of spirally-arranged water-tubes, said tubes dividing the interior of the flue into two independent compartments.

50 2. In a tubular boiler, a plurality of flues extending therethrough, and a series of spirally-arranged water-tubes inclosed in and extending longitudinally of each of said flues.

55 3. In a tubular boiler, a boiler-shell, a plurality of flues therein, a plurality of water-tubes extending longitudinally of each flue,

said water-tubes dividing the interior of the flues longitudinally into a plurality of sinuous compartments.

4. In a tubular boiler, a boiler-shell, a plurality of flues therein, and a plurality of water-tubes extending longitudinally of each flue, said water-tubes dividing the interior of the flue longitudinally into a plurality of independent compartments. 65

5. In a boiler, a boiler-shell, a plurality of flues therein, each of said flues having at each end a header extending across the interior thereof, a plurality of water-tubes connected to said headers, said water-tubes having communication at their ends with the interior of the boiler-shell. 70

6. In a boiler, a boiler-shell, a plurality of flues therein, headers on the interior of and extending transversely across each flue near 75 its ends, and spirally-arranged water-tubes connecting said headers, the ends of said water-tubes having communication with the interior of the boiler-shell.

7. In a boiler, a boiler-shell having a plurality of flues therein, headers in the interior of each flue near each end thereof, a water-tube connecting the headers in each flue and extending centrally of the flue, and a port extending transversely through the flue and 85 through each header whereby said water-tube has a free communication with the interior of the boiler-shell near each end thereof.

8. In a boiler, a boiler-shell having a plurality of flues therein, a header extending across 90 the interior of each flue near each end thereof, spirally-arranged water-tubes connecting the headers in each flue, and an opening extending transversely through the flue and each header and furnishing communication between the water-tubes and the interior of the shell. 95

9. In a boiler, a boiler-shell having a plurality of flues, a series of spirally-arranged water-tubes inclosed by each flue, and extending 100 longitudinally thereof, the water-tubes of each series being in contact with each other and the outer tubes of the series engaging the inner wall of the flue, whereby each flue is divided into two sinuous compartments. 105

In testimony whereof I have signed my name to this specification in the presence of two subscribing witnesses.

JAMES M. McCLELLON.
